MAIL BOX SIGNAL

William Luther Dysart, Louisville, Ky.

Application August 7, 1933, Serial No. 684,067

1 Claim. (Cl. 232—34)

This invention has for its object the provision of a very simple and inexpensive signal for use upon rural delivery mail boxes whereby the carrier may be advised as to whether the mail box 5 contains letters to be taken up, and may indicate to the occupants of the adjacent dwelling that mail has been deposited in the box. The invention is illustrated in the accompanying drawing and will be hereinafter fully described, the novel 10 features being particularly defined in the appended claim.

In the drawing,

Figure 1 is an elevation of a mail box having my improved signal applied thereto,

Figure 2 is an enlarged vertical section of the signal, and

Figure 3 is a detail section on the line 3—3 of Figure 2.

The mail box 1 may be of the usual or any preferred design. In carrying out the present invention, there is provided a post 2 which is formed with a base or foot 3 adapted to rest upon the top of the box and impart stability to the post, the post having a central bore opening through its upper end and having a drain passage 4 leading through its side from the lower end of the bore. In mounting the device upon the mail box an opening, indicated at 6, is formed through the top of the box and a lag screw 7 is inserted 20 through this opening after being engaged in the lower end of the post, a nut 8 being mounted upon the lower end of the screw and turned home against the underside of the top of the box so as to firmly secure the device in position, as will be 25 understood upon reference to Figure 2. A shaft 9 is disposed vertically within the post and is journaled in the bore thereof, the upper portion of the shaft rising from the post and carrying a signal plate 10. The signal plate may be given 30 any preferred outline and is illustrated as a dart or arrow pointing downwardly. The plate will preferably be formed of sheet metal and will present its edge or its side to an observer, according to the position of the observer and the position 35 in which the signal is set. In order that the signal may be set in a desired position, a handle 11 is firmly secured to the shaft 9 and extends radially therefrom through a slot 12 provided therefor in the post, as clearly shown. The slot 40 12, as shown most clearly in Figure 3, extends through one-quarter of the circumference of the post and, as shown in Figure 1, a downturned notch 13 is provided at each end of the slot. The

handle may be moved easily from end to end of the slot and may be seated in either notch so that it will be set to present its side or its edge to view from the corresponding dwelling, or to the view of the carrier approaching the box. Any rain or moisture which may work into the post will escape through the slot 12 or the drain opening 4.

When the owner of the mail box deposits mail in the box to be taken up by the carrier, he will 5 grasp the handle 11 and turn it to such a position that the signal plate 10 will present its side to the view of the carrier approaching the box. The signal will thus be plainly visible to the carrier and he will know that mail has been placed 10 in the box to be collected by him. If the carrier has mail to be delivered to the owner of the box, he will place said mail in the box and then turn 15 the signal so that the side of the signal plate will be presented to the view of the occupants of 20 the adjacent dwelling so that they will understand that mail has been left for someone in the house.

The device is exceedingly simple and may be 25 readily observed by interested persons inasmuch as it is mounted upon the top of the box and is not hidden by the side of the box from any point of view. The base serves to establish a very firm 30 footing upon the box so that the post may be easily secured to the box and will be firmly held against dislodgment. The signal shaft may be turned easily at all times and the post constitutes a very substantial housing for the shaft 35 which will effectually protect it from weather elements and prevent its operation being clogged by any collection of snow or other matter.

Having thus described the invention, I claim:

A signal for the purpose set forth comprising a post, a fastening device insertable through the 40 top of a mail box and carried by the lower end of the post to secure the device upon the box, a vertical signal shaft rotatably fitted within a vertical bore in said post, the shaft rising beyond the upper end of the post, a signal carried by the 45 shaft above the post, the post having a horizontal slot in its side and depending notches at the ends of the slot, and a handle fixed to the shaft and extending radially through said slot and engageable in the notches at the ends of 50 the slot to set the signal and hold it in a set position.

WILLIAM LUTHER DYSART. [L.S.]
